TAPE DISPENSER FRAME

Millard Pretzfelder, Jr., Plandome, N. Y., assignor to Paper Novelty Manufacturing Company,
Brooklyn, N. Y., a corporation of New York

Application June 30, 1950, Serial No. 10,896

Term of patent 14 years

(Cl. D74—1)

To all whom it may concern:

Be it known, that I, Millard Pretzfelder, Jr., a citizen of the United States of America and resident of Plandome, L. I., county of Nassau, State of New York, have invented a new, original, and ornamental Design for a Tape Dispenser Frame, of which the following is a specification, reference being had to the accompanying drawing, forming a part thereof, in which

Fig. 1 is a plan view of a tape dispenser frame embodying my design;

Fig. 2 is a side view thereof;

Fig. 3 is a bottom view thereof; and

Fig. 4 is a perspective view thereof.

My design for a tape dispenser frame is characterized by its configuration in connection with the button-like element located on the plate immediately above the cutting lip.

I claim:

The ornamental design for a tape dispenser frame, substantially as shown and described.

MILLARD PRETZFELDER, JR.
